UNITED STATES PATENT OFFICE.

ADOLPH G. KAUFMAN, OF NEW YORK, N. Y.

VAPORIZER-GUIDE.

1,345,448.

Specification of Letters Patent.

Patented July 6, 1920.

Application filed September 12, 1919. Serial No. 323,372.

To all whom it may concern:

Be it known that I, ADOLPH G. KAUFMAN, a citizen of the United States, residing at New York, in the county and State 5 of New York, have invented a new and useful Vaporizer-Guide, of which the following is a specification.

This invention relates to lanterns, and especially to that class where the hydrocarbon fluid is vaporized and burned in connection with incandescent mantles; and the object of the invention is to provide a lantern of this kind with a guide for the vaporizer so that the vaporizer, or generator, 15 can be inserted between the mantles without danger of breaking the same, and without having to remove the globe, or supporting plate.

The invention is illustrated in the accompanying drawing in which—

Figure 1, is a sectional elevation of a lantern, or portion thereof, constructed in accordance with my invention;

Fig. 2, is a section thereof, on the line 25 2—2 of Fig. 1;

Fig. 3, is a sectional view of a part of the lantern, taken on the line 3—3 of Fig. 1, looking in the direction of the arrows; and

Fig. 4 is a face view of a part of the lantern carrying the mantles, and the guide leading to the vaporizer entrance in the burner head.

In the drawing, like numerals of reference refer to the same parts in each of the 15 views.

In practice I provide a lantern having a reservoir 5, vaporizer 6, and air-intake tube 7, with a burner head 8, which is provided with an extension 9, with which the tube 7 is connected; and in the face of this extension I provide a channel 10, leading to the orifice 11, in the horizontal part of the burner head 8 adapted to receive the nozzle of the vaporizer 6.

The globe supporting plate 12 is provided with a central orifice 13 over the preheating cup 14 on the vaporizer 6, so that the ignition fuel may flow down the channel 15 in the plate 12 and enter the same; and the 5 plate 12 is provided with a slot 16 communicating with the orifice 13 and extending outwardly sufficiently so that the vaporizer 6 can be drawn out into the position indicated with dotted lines in Fig. 1 in re- 10 moving the same from the lantern, or inserting the same. By this arrangement the

entrance of air within the globe 17 of the lantern can be restricted while providing means for the easy removal, and renewal of the vaporizer, or generator.

60

In operation, when it is desired to remove the vaporizer, the same is unscrewed from its connection with the burner valve 18, and may then be drawn out till the vaporizer cup, or preheating cup 14 is free from the 65 burner valve and reservoir as clearly shown, when the vaporizer may be drawn out. When it is desired to reinsert the vaporizer 6, it is passed upward within the lantern through the slot 16, till the end of the vaporizer strikes the channel 10 formed in the extension 9 of the burner head, when the end of the vaporizer is guided to the orifice 11 in the burner head between the mantles 19 without danger of breaking either 70 mantle.

75

It will thus be seen that by providing the guide in the burner head and extension, and by providing the slot 16 in the base plate to coact therewith the vaporizer can be easily 80 renewed without breaking the mantles. This is specially facilitated by fixing the cup 14 on the vaporizer 6 so that the vaporizer can be handled with the cup, or by using the cup as a tool to unscrew the vaporizer, and in screwing the same in position after the end of the vaporizer enters the orifice 11 in the burner head. It will 85 thus be seen that the slot 16 coacts with the channel 10 to form the guide, or to guide 90 the vaporizer to its position as the slot is preferably so located that when the vaporizer is inserted through the same and passed upwardly it will be in line with the channel that the two may act together to 95 guide and direct the vaporizer to the orifice 11 in the burner head.

95

It will be understood that the orifice 13 in the plate 12 might be made larger in which event the slot 16 could be omitted, and the 100 guide on the burner head would be sufficient to guide the vaporizer to the orifice in the burner head; but it would not be desirable to enlarge the orifice 16 sufficiently for this purpose as more air would likely enter the 105 lantern than would be desirable in operating the same. For this reason I prefer to make the orifice 13 small, and to provide the slot 16, as the slot will not admit much air, and is a very good assistant to the guide in the 110 burner head to direct the vaporizer to the proper position.

It is usual to use two mantles in a lantern of this kind; and when two mantles are used the orifice in the burner head is preferably located between them. In such a construction it is very desirable to have a guide to prevent the breakage of the mantles in the renewal, or "needling" of the vaporizer, where the vaporizer is removed for the purpose of "needling". It is also desirable to provide means to attend to the vaporizer without the necessity of removing the globe 17; and it is also desirable to provide a stop 18 so the vaporizer will not travel too far in the guide, but will enter the orifice in the burner head when it reaches it.

I claim:

1. A burner head for an incandescent light having a guide for the vaporizer extending vertically below the top of the mantle and laterally from the vertical portion to the vaporizer entrance in the burner head.
2. A burner head for an incandescent light provided with a plurality of mantles, said head having a guide for the vaporizer extending vertically below the top of the mantles and laterally from without the zone of the mantles to the vaporizer entrance in the burner head.
3. In an incandescent light having means for generating gas from a hydrocarbon fluid and burning the same in connection with an incandescent mantle, a burner head having a dependent portion connected with the supporting standard, said extension having a guide in one side thereof adapted to direct the vaporizer toward the burner head, and said burner head having a guide for the vaporizer from said dependent portion to the vaporizer orifice in the burner head.
4. In an incandescent light having means for generating gas from a hydrocarbon fluid and burning the same in connection with an incandescent mantle, a burner head having a side arm, an air-intake tube communicating with said arm, and a guide

adapted to direct the vaporizer nozzle to the receiving orifice in said head, said guide having a vertical portion extending parallel with the air-intake tube adapted to direct the vaporizer upward toward the burner head, and a horizontal portion leading from said vertical portion to the vaporizer entrance in the burner head.

5. In an incandescent light having means for generating gas from a hydrocarbon fluid and burning the same in connection with a plurality of incandescent mantles, a burner head having a vaporizer entrance intermediate of said mantles, and having a side arm with a dependent portion, an air-intake tube connected with said extension and in communication with said arm, said head having a guide extending vertically along said dependent portion and horizontally along the bottom of the head from said portion to the vaporizer entrance whereby the vaporizer may be directed upwardly along said air-intake tube and laterally to said orifice.

6. The herein described lantern comprising a reservoir, vaporizer, and burner head with supporting air-intake tube, said lantern being inclosed with a globe mounted on a supporting plate, and the burner head carrying two mantles with an orifice between them adapted to receive said vaporizer, said plate having a central orifice, and a slot extending from said orifice outward from said air-intake tube, said burner head having a vertical guide extending below the top of the mantles, and a horizontal guide extending from the vertical guide to the vaporizer entrance, for the purpose set forth.

7. In a lantern, the combination of a guide for the vaporizer in the burner head, and a slot in the globe supporting plate adapted to co-act with said guide in directing the vaporizer to the entrance in the burner head.

Dated this 8th day of September, 1919.

ADOLPH G. KAUFMAN.
